CLAIM

We claim the ornamental design for a shower faceplate for shower device, as shown and described.

DESCRIPTION

This application is a related to application Ser. No. 29/415, 587, filed Mar. 12, 2012, to application Ser. No. 29/450,310, filed Mar. 15, 2013, to application Ser. No. 29/450,306, filed Mar. 15, 2013, and to application Ser. No. 29/450,323, filed Mar. 16, 2013, the entire contents of which are hereby incorporated by reference.

FIG. 1 is a front perspective view of a faceplate for a shower device, such as a showerhead or a hand shower.

FIG. 2 is a rear perspective view of the faceplate shown in FIG. 1.

FIG. 3 is a front view of the faceplate shown in FIG. 1.

FIG. 4 is a rear view of the faceplate shown in FIG. 1.

FIG. 5 is a left side view of the faceplate shown in FIG. 1, the right side view being substantially a mirror image thereof.

FIG. 6 is a top view of the faceplate shown in FIG. 1.

FIG. 7 is a bottom view of the faceplate shown in FIG. 1; and,

FIG. 8 is a rear perspective cross-sectional view of the faceplate shown in FIG. 1 to illustrate contours of the faceplate. Portions of the design illustrated as transparent or translucent may be transparent, translucent, and/or opaque, in any combination.
